UNITED STATES PATENT OFFICE.

EDWARD L. HARRINGTON, OF ERIE, PENNSYLVANIA, ASSIGNOR TO G. H. WILLIAMS COMPANY, OF ERIE, PENNSYLVANIA, A CORPORATION OF PENNSYLVANIA.

FLOOR SCRAPER.

Application filed September 24, 1925. Serial No. 58,465.

This invention is designed to scrape floors and one use for which it is particularly advantageous is the scraping of sand on foundry floors to place the sand in position to be operated upon by the sand carriers. In carrying out the invention the scraper is preferably operable from a hoist which is usually available in such places and in the present apparatus the scraper is so designed. Features and details of the invention will appear from the specification and claims.

The invention is illustrated in the accompanying drawings as follows:

Fig. 1 shows a side elevation of the device, parts being broken away to better show construction.

Fig. 2 a plan view of the scraper.

Fig. 3 a sectional perspective view of the catch on the line 3—3 in Fig. 1.

Fig. 4 a section on the line 4—4 in Fig. 1.

The track frame is made up of side channels 1—1 and center channels 2—2, the center channels being back to back so that the faces of the channels 2—2 are opposed to the channels 1—1. These channels are inclined toward the center and a tie bar 3 is arranged outside of the channels 1—1 and connected to the channels by a strut 4. The channels are tied together by cross plates 6 which are mounted slightly above the channels so as to give clearance through brackets 5 which are secured to the channels and the cross plates. End bars, or plates 7, are secured to the ends of the channels.

Opposing scrapers in the form of buckets 8 are mounted on the track. These scrapers have the bottom edges forming the scraping edge and a half-barrel shaped vertical wall 11.

The scrapers are slidingly mounted in the track frame. Brackets 12 are secured at the two sides and upper edges of the scrapers and have the rollers 13 which extend into the channels 1. Brackets 14 extend upwardly from the rear edges of the buckets and have rollers 15 which extend into the channels 2. These brackets are so shaped as to hold the scraper with the bottom in a horizontal position notwithstanding the inclination of the channel tracks.

A trolley frame is formed of two side plates 16. Rollers 17 are mounted on the inside of the side plate and extend into the channels 2. A pin 18 extends through the side plates 16, the ends projecting outwardly from the side plates. A catch lever 19 is

pivotedly mounted on the pin 18. A pin 20 connects the inner ends of the catch levers at each side of the trolley and thus make the two catch levers into a rigid U-shaped structure. The catch lever is provided with a catch 21 which is adapted to engage the catch shoulders 22 on a cross frame 22a in the upper part of the bucket. Cables 23 are secured by eyes 24 on the pins 18 and extend under pulleys 25 mounted in the head plates 26 of the track frame. The cables are looped over an evener bar or hanger 27 and a hoist hook 28 engages the hanger 27. A roller 29 is journaled on the pin 20 and engages a spring 30 arranged under the channels 2 as the trolley moves along these channels.

Weights 31 are arranged on the catch levers 19 and are of sufficient magnitude to form a preponderance sufficient to tip the outer ends of the levers downwardly so as to release the catch 21 from the catch shoulders 22, when relieved of pressure.

The operation of the device is as follows:— With the parts in the position shown in Fig. 1, the trolleys are at their outer part. The roller 29 is operated upon by the spring 30 to yieldingly force the catch 21 into engagement with the catch shoulder 22. With a hoisting movement of the hoist 28 the trolleys are drawn inwardly and the scrapers are carried with the trolleys because of the engagement of the hooks or catches 21 with the catch shoulders. The frame is of sufficient weight so that this inward movement will take place without appreciably lifting the scrapers and as the scrapers move inwardly the frame is gradually lowered to compensate for the inclination. The engaging surface between the catch 21 and the shoulder 22 is slightly undercut so that as long as the pressure is maintained on the cables and consequently on the hooks the weight 31 is not sufficient to disengage these hooks. The scrapers are, therefore, drawn toward each other as far as desired by a mere hoisting operation of the hoist. When the scrapers have reached the inward position as far as it is desired the hoist is slackened and as the cables are slackened the weights on the catches swing the catch levers so as to release the catches 21 from the shoulders 22.

As the hoist is again lifted the scrapers roll down the inclined tracks formed by the frames to their outer position. The hoist is then again lowered and the trolley moves down the

tracks to the outer position, the springs 30 operating on the rollers throwing the catches again into engagement. I prefer to provide the shoe 32 around the bottom edge of the scrapers as a guard against digging into the floor.

What I claim as new is:—

- 5 1. In a floor scraper, the combination of a track frame; scraper blades opposingly faced and slidingly and rigidly mounted on the frame; hoisting means; and mechanism acting with the frame and hoisting means moving the scrapers toward and from each other.
- 10 2. In a floor scraper, the combination of a track frame; bucket-shaped scraper blades opposingly faced and slidingly and rigidly mounted on the frame; hoisting means; and mechanism acting with the frame and hoisting means moving the scrapers toward and from each other.
- 15 3. In a floor scraper, the combination of a track frame; scraper blades opposingly faced; roller bearings between the scraper blades and the frame maintaining a rigid connection between the blades and frame; a hoisting means; and mechanism acting with the frame and hoisting means moving the scrapers toward and from each other.
- 20 4. In a floor scraper, the combination of a track frame; scraper blades opposingly faced and slidingly mounted on the frame; a catch carrier for each blade slidingly mounted on the frame; catches on the carriers adapted to engage the blades; a hoist; and means actuated by the hoist actuating the carriers and blades toward and from each other.
- 25 5. In a floor scraper, the combination of a track frame; scraper blades opposingly faced and slidingly mounted on the frame; a catch carrier for each blade slidingly mounted on the frame; catches on the carriers adapted to engage the blades; a hoist; and means actuated by the hoist actuating the carriers and blades toward and from each other.
- 30 6. In a floor scraper, the combination of a track frame; scraper blades opposingly faced and slidingly mounted on the frame; a catch carrier for each blade slidingly mounted on the frame; catches pivotally mounted on the catch carriers and adapted to engage the blades; means tending to release the same as the carriers and blades leave the end of the frame; and means at the ends of the frame moving the catches into engagement.
- 35 7. In a floor scraper, the combination of a track frame; scraper blades opposingly faced and slidingly mounted on the frame; a catch carrier for each blade slidingly mounted on the frame; catches pivotally mounted on the catch carriers and adapted to engage the blades; means tending to release the same as the carriers and blades leave the end of the frame; and means at the ends of the frame moving the catches into engagement.

faced and slidingly mounted on the frame; a catch carrier for each blade slidingly mounted on the frame; catches pivotally mounted on the catch carriers and adapted to engage the blades; means tending to release the same as the carriers and blades leave the end of the frame; means at the ends of the frame moving the catches into engagement; a hoist; and means actuated by the hoist actuating the carriers and blades toward and from each other.

8. In a floor scraper, the combination of a track frame having oppositely and inwardly inclined track sections; scraper blades opposingly faced and slidingly and rigidly mounted on the frame; hoisting means; and mechanism acting with the frame and hoisting means moving the scrapers toward and from each other.

9. In a floor scraper, the combination of a track frame having oppositely inclined track sections; scraper blades opposingly faced and slidingly mounted on the frame; catch carriers for each blade slidingly mounted on the frame; catches mounted on the inclined track sections; catches on the carriers adapted to engage the blades; a hoist; and means actuated by the hoist actuating the carriers and blades toward and from each other.

10. In a floor scraper, the combination of a track frame having oppositely inclined track sections; scraper blades opposingly faced and slidingly mounted on the frame; catch carriers on each blade slidingly mounted on the frame; catches mounted on the inclined track sections; catches on the carriers adapted to engage the blades; a hoist; and means actuated by the hoist actuating the catches, carriers and blades toward and from each other.

11. In a floor scraper, the combination of open bottom scraping blades; and mechanism actuated and controlled entirely from a single hoisting means hoisting and actuating the blades toward and from each other closing and opening the same for scraping material into a heap.

12. In a floor scraper, the combination of a track frame; scraper blades opposingly faced and slidingly and rigidly mounted on the frame; and mechanism actuated and controlled entirely from a single hoisting means hoisting and actuating the blades toward and from each other closing and opening the same for scraping material into a heap.

In testimony whereof I have hereunto set my hand.

EDWARD L. HARRINGTON.
